UNITED STATES PATENT OFFICE.

LOUIS E. BALTZLEY, OF GLEN RIDGE, NEW JERSEY.

CLOSURE.

Application filed November 19, 1924. Serial No. 750,795.

To all whom it may concern:

Be it known that I, LOUIS E. BALTZLEY, a citizen of the United States, and a resident of Glen Ridge, Essex County, and State of New Jersey, have invented certain new and useful Improvements in Closures, of which the following is a specification.

The present invention relates to closures for bottles, jars and other containers.

- 10 The objects of the invention are to provide a tight-fitting closure which can be readily applied and removed; which may be used repeatedly without loss of its tight sealing qualities; which will automatically adapt itself to such variations in size as ordinarily occur in the manufacture of the bottles or containers with which the invention is used; which will be inexpensive, easily manufactured and adapted to be used 20 with the present bottle sealing equipment and applied to bottles or other containers of standard form.

These objects are attained through certain novel features of construction, combination and relation of parts as will be clear 25 from the following specification wherein one of the commercial embodiments of the invention is disclosed.

Figures 1 and 2 in the drawing accompanying and forming part of this specification, are part sectional views illustrating the closure in the form of a bottle cap and showing it first as secured in sealed relation 30 on a bottle neck and then released, ready for removal.

Figure 3 is a top plan partial sectional view of the cap.

Figure 4 is an underneath or bottom plan view of the cap with one of the gripping 40 fingers partially removed and shown in section.

The body of the closure is shown as a substantially flat disc 5 having an annular bead 6 about the rim of the same and dependent spring fingers 7 curled inward at their lower ends at 8 and terminating in the outwardly projecting tips or lugs 9.

The annular bead 6 provides a shoulder at the upper ends of the spring fingers 7 and the out-turned lugs 9 collectively form a second shoulder, at the lower ends of the fingers for limiting the up and down sliding movements of a clamping ring 10 which is engaged about the fingers and serves, as shown in Figure 1, to force the tips of the fingers into holding engagement beneath

the bead or shoulder 11 on the neck of the bottle or other container 12.

The ring 10 is of special construction consisting of a single length of strip stock disposed on edge and having its ends connected by a lock seam such as indicated at 13 in Figure 3, the ring so formed being then flanged outwardly at the upper edge as indicated at 14 to provide an outstanding annular shoulder for manipulation purposes. It will be observed that the flanging of this ring turns the outer or upper portion 13^a of the lock seam substantially at a right angle to its original plane, thus fixing the 70 joined parts so that there can be no edge-wise slippage of the seam. A permanent, non-stretching joint is thus provided without any waste of material. A sealing disc or discs 15 is or are usually employed in the cap which may be held in place by suitable adhesive or be held by engagement inside the bead 6 in the rim of the cap.

The cap is preferably formed up out of 80 spring sheet metal and the fingers which are bent down from the rim of the cap may be left in their original flat state, as shown, so as to introduce an additional element of adjustability, the edges of these flat fingers being engaged by the contracting ring, as 85 shown in Figure 2, and bent to more or less curvilinear cross section to fit the particular bottle to which the cap is applied.

The bead or bend at the upper ends, where the securing fingers are joined to the cap 90 body, allows for a certain amount of elongation of the fingers and a further degree of elongation is afforded at the bends on the lower ends of the fingers so that the caps will adjust themselves to possible variations 95 in the shape of the locking shoulder or the distance of the locking shoulder from the mouth of the bottle. The closure is thus self-adjusting and capable of forming a gas and liquid-tight joint with the bottles or containers for which it is intended.

As the parts are not deformed in applying or removing, the closure may be used 100 repeatedly and because of its structure, will maintain its perfect sealing characteristics, even after it has been applied and removed a great number of times. The edgewise position of the ring provides an additional element of resiliency enabling the closure to 105 adapt itself the more readily to variations 110 in the contour of the bottle neck, etc.

The outstanding flange on the finger-clos-

ing ring provides a shoulder for engagement by the ring of an ordinary crown cap sealing machine so that these closures may be applied by the capping machines extensively used in bottling establishments. The closure does not, however, require any special opening tool, as the edge of the curled over flange provides a handy grip for engagement by the fingers enabling the ring to be easily shifted to the released position shown in Figure 2, by simply pulling upward on the same by the fingers. In such a case, the thumb may be rested on top of the cap while the fingers of the same hand are engaged beneath the flange to raise the clamping ring. When the ring is raised the cap is then simply held in place by the light spring engagement of the fingers over the bead of the neck so that the cap can then be removed by simply lifting it off the neck.

The outward spring of the holding fingers when they are released tends to retain the ring in the upper position shown in Figure 2, so that in this relation of the parts the closure may be applied to and removed from the container without shifting the ring, it being held to the container at such times only by the spring gripping force of the fingers. When, however, the ring is forced down against the stop lugs 9, the fingers will be bent inward into locking engagement beneath the shoulder of the container and will not let go until the ring is shifted to the release position.

It will be evident that instead of being of circular form, the closure may be made in elliptical, angular or other shapes to fit different styles of containers and that in each instance the ring will have the effect of connecting the holding fingers to the shape of the container and securing the same thereto in tight-fitting relation. As the downward movement of the ring over the fingers is limited by the stop shoulders at the lower ends of such fingers, it is evident that in addition to having the effect of closing the fingers, the ring also serves to force the closure all the more firmly to its seat on the mouth of the container.

50. What is claimed is:

1. A closure having dependent spring fingers, stop shoulders on the closure at the upper and lower ends of said fingers and a finger-closing ring slidably engaged about the fingers between said shoulders, said ring having an outturned flange at one edge forming an abrupt shoulder facilitating operation of the same, and both removal and replacement of the closure by said ring.
2. A closure having dependent spring fingers, stop shoulders at the upper and lower ends of said fingers and a finger-closing ring slidably engaged about the fingers between said shoulders, the shoulder at the upper ends of the fingers being provided by an out-

standing bead connecting the fingers with the rim of the closure and the shoulders at the lower ends of the fingers consisting of outwardly extended lugs on the lower ends of the fingers.

3. A closure having dependent spring fingers provided with lugs for engagement with the bead of a bottle neck and providing stop shoulders, a closing ring slidably engaged about said fingers limited in downward movement over the fingers by engagement with the stop shoulder lugs on the spring fingers and provided with an out-turned flange enabling digital operation of the same.

4. A closure having dependent spring fingers provided with lugs for engagement with the bead of a bottle neck, a closing ring slidably engaged about said fingers and provided with an out-turned flange enabling digital operation of the same and stop shoulder means at the upper ends of the dependent spring fingers limiting the upward movement of the ring to thereby enable the closure being lifted off the bottle neck by means of the outstanding flange on the ring.

5. As an article of manufacture, a ring consisting of a strip of sheet metal having its ends secured by a lock seam and turned over to form an angularly projecting flange locking the parts of the seam against edgewise displacement.

6. As an article of manufacture, a ring of sheet metal having a lock seam joint with a portion turned substantially at a right angle to lock the elements of the seam against sliding displacement.

7. The process of constructing a ring which comprises joining the ends of a sheet metal strip by a lock seam and then turning the elements of said lock seam for a portion of their length substantially at a right angle to thereby lock the elements of the seam against edgewise displacement.

8. The process of permanently uniting two sheet metal elements which comprises joining them by a lock seam and then turning a portion of the lock seam substantially at a right angle to lock the elements of the seam against edgewise displacement.

9. A closure having dependent gripping fingers, a finger closing ring slidably engaged about said fingers and shoulders on the closure limiting the up and down movement of said ring over the fingers, whereby said closure may be applied and removed by manipulation of said ring, the shoulder limiting upward movement of the ring comprising an annular bead at the junction of the fingers with the rim of the closure and the shoulders limiting downward movement of the ring comprising outwardly bent lugs on the free ends of the fingers.

10. A closure having dependent gripping fingers, a finger closing ring slidably en-

gaged about said fingers and shoulders limiting the up and down movement of said ring over the fingers, whereby said closure may be applied and removed by manipulation of said ring, the shoulder limiting upward movement of the ring being provided by an outstanding bead connecting the fingers with the rim of the closure.

11. A closure having dependent fingers for interlocking engagement with the neck of a container, a finger closing ring slidably engaged over said fingers and outwardly projecting stop shoulders on said fingers projecting outwardly beyond the normal plane of the fingers, thereby limiting downward movement of the ring thereover to en-

able downward thrust on said ring to close the fingers and also to force the closure to a seat on the container.

12. A closure comprising a cap engageable over a bottle neck or the like and having dependent spring fingers engageable with the sides of the bottle neck, said fingers being substantially flat transversely in nonconformity to the curvature of the neck and an encircling ring for closing the fingers on the neck and for bowing the fingers transversely to compensate for variations in size and roundness of the bottle neck.

In witness whereof, I have hereunto set my hand this 24th day of October, 1924.

LOUIS E. BALTZLEY.
